(57) **CLAIM**

The ornamental design for an indoor air quality detector, as shown and described.

DESCRIPTION

FIG. 1 is a left side view of an indoor air quality detector, the right side being a mirror image thereof.

FIG. 2. is a back side view of the indoor air quality detector of FIG. 1.

FIG. 3. is a bottom side view of the indoor air quality detector of FIG. 1.

FIG. 4 is a front side view of the indoor air quality detector of FIG. 1

FIG. 5 is a bottom isometric view of a right side of the indoor air quality detector of FIG. 1

FIG. 6 is a top isometric view of a right side of the indoor air quality detector of FIG. 1; and,

FIG. 7 is a top view of the indoor air quality detector of FIG. 1.

The broken lines showing the display screen do not form a part of the claimed design. The dashed-dotted line shows the boundary between the part of the claimed design and the unclaimed part of the design.
